UNITED STATES PATENT OFFICE.

EDWARD J. BARCALO, OF BUFFALO, NEW YORK.

MATTRESS.

Application filed May 17, 1922. Serial No. 561,620.

To all whom it may concern:

Be it known that I, EDWARD J. BARCALO, a citizen of the United States, residing at Buffalo, in the county of Erie and State of New York, have invented a new and useful Improvement in Mattresses, of which the following is a specification.

This invention relates to mattresses for beds, and more particularly to improvements 10 in mattresses of the kind extensively used at the present time, in which the filling is composed of felted cotton or cotton batting.

One object of the invention is to so make the mattress, that a desirable mattress, affording the maximum comfort, which will have long life and retain its resiliency and original shape, can be sold at a much lower price than mattresses of present known constructions of equal comfort and desirability.

20 Other objects of the invention are to produce a mattress which is soft and comfortable, has great resilience, and will not sag or acquire a depression in the middle portion thereof, as is so common, and in which 25 the sides are prevented from bulging outwardly and spoiling the original straight-sided shape of the mattress; also to produce a mattress which has the recognized, soft, comfortable surface of the felted cotton mat- 30 tress, and the resilience of a good quality hair mattress, but which can be produced and sold at less expense than a hair mattress; and also to improve mattresses in the 35 other respects hereinafter described and set forth in the claim.

In the accompanying drawings:—

Fig. 1 is a plan view partly in section, of a mattress embodying the invention.

Fig. 2 is a transverse section thereof.

40 Fig. 3 is an enlarged fragmentary trans- verse section.

The tick or case 10 of the mattress can be made of any usual or suitable material and construction, having the usual straight, upright side and end walls or portions 11 and 12. The filling or stuffing 13 of the mattress consists of a main body of suitable material, preferably felted cotton in layers, and a resilient insert pad 14 which is of smaller 45 dimensions than the mattress, and is secured in the middle portion of the main body of filling between the sides and ends of the mattress. This insert pad consists of suitable filling and a bag or envelope in which the 50 filling is confined and retained intact, and which bag is anchored in the mattress so as 55 to hold the insert pad securely in place centrally in the mattress. The usual tufting cords 15 of the mattress pass through the insert pad and assist in preventing it from 60 shifting in the mattress, and the enclosing bag of the pad prevents the pad filling from pulling apart or spreading and thus destroying 65 the efficiency of the pad. For the filling of the pad, a material having a greater resiliency than the main filling of the mattress is preferably employed, for instance, a good grade of curled hair. The insert pad of this more resilient material increases the resiliency or elasticity of the mattress, en- 70 suring a springy, comfortable bed, and being normally compressed in the mattress, it tends to expand and press outwardly or hold up the middle portion of the mattress in its original shape, preventing the formation of 75 a depression which lessens the comfort of the mattress and spoils its appearance. In the preferred construction of the insert pad, it is formed in two sections or halves above and below a central anchoring strip of ma- 80 terial 16, which extends from side to side of the mattress midway between the top and bottom thereof, and is secured to the opposite side walls or edges of the mattress, the two sections of the pad filling being enclosed 85 on the opposite sides of this securing strip by separate pieces of material 17 and 18, stitched around their edges to the anchoring strip 16. In other words, the insert pad is in effect formed by two thin, enclosed or 90 covered cushions above and below the central anchoring piece 16. By this construction there is a continuous piece of material 16 which extends straight through the pad from one side wall to the opposite side wall 95 of the mattress so that when the center of the mattress is depressed by the weight thereon, this anchoring strip 16 tends to resist downward deflection and to pull inwardly on the side walls of the mattress, 100 having the double effect of holding the insert pad up and opposing the depression of the upper surface of the mattress, and also of preventing the side walls of the mattress from bulging outwardly from the 105 original, straight, upright shape thereof. As the insert pad is normally compressed in the mattress filling, it receives pressures through the upper parts of the mattress filling and distributes these pressures through 110 a relatively large area of the lower part of the resilient filling in the mattress, and at

the same time the central or anchor strip of material 16 prevents the filling material subjected to said pressures from spreading laterally by anchoring or holding the upper right side walls of the case 10.

For securing the anchoring piece 16 to the side walls of the mattress tick, securing flaps 19 are preferably attached to the anchoring piece near its opposite ends so that the anchoring piece has at each end two securing flaps, one adapted to extend upwardly and the other downwardly between the mattress filling and the side walls of the tick, see Fig. 3. These securing flaps are secured to the side walls of the tick by long stitching 20, such as is commonly employed in mattresses for securing the edge portions of the filling to the side and end walls of the tick. These stitches extend through the side walls of the tick and the securing flaps 19, and pass up or down through adjacent portions of the filling and then back again through the securing flaps and side walls without passing out through the top and bottom covering of the tick, so that the stitches are not exposed or seen at the top and bottom of the mattress. In this way the securing strip 16 is very securely fastened to the opposite edges of the mattress, and the insert pad is firmly held in place centrally in the mattress. By extending the anchoring strip 16 centrally through the insert pad so as to form a substantially straight or taut connection between the opposite side walls of

the tick, as explained, the function of this member in retaining the mattress in shape, as explained, is much more pronounced and effective than would be securing pieces extending only from the edges of the insert pad to the edges of the mattress. This is for the reason that with the latter arrangement, the insert pad necessarily flattens or expands laterally somewhat under the weight on the mattress, and this would have a tendency to slacken the securing piece and permit the bulging of the sides of the mattress, whereas by the construction shown, any depression of the insert pad by the weight on the mattress places the anchoring piece 16 under greater tension and increases the inward pull on the side walls of the mattress tick.

I claim as my invention:

In a mattress the combination with the enclosing case, and the filling, of an anchoring strip passing through the mattress filling between the top and bottom thereof from side to side of the mattress and secured to the opposite side edges of the mattress case, and an insert pad comprising two sections of resilient filling material arranged above and below said anchoring piece and confined in containers connected to the top and bottom of said anchoring strip, said insert pad being arranged in the mattress between the sides and ends thereof.

EDWARD J. BARCALO.
